UNITED STATES PATENT OFFICE.

JONATHAN WAINWRIGHT, JR., OF PHILADELPHIA, PENNSYLVANIA.

PAPER BOTTLE

Application filed June 26, 1922. Serial No. 570,997.

To all whom it may concern:

Be it known that I, JONATHAN WAINWRIGHT, Jr., a citizen of the United States, residing at Philadelphia, in the county of 5 Philadelphia and State of Pennsylvania, have invented new and useful Improvements in Paper Bottles, of which the following is a specification.

This invention relates to sanitary paper 10 bottles, and while here shown as particularly applied to milk bottles, it is to be understood that it may be utilized for producing bottles to contain other substances.

One of the principal objects is to produce 15 a device of this nature which shall closely follow the lines and shape of the present standard glass milk bottle so as to be capable of being filled and capped by the equipment at present in use for filling and capping the glass bottle.

Another object is to produce a device of 20 this nature which is of simple construction, cheap to manufacture and highly efficient for the purpose for which it is intended.

With these and other objects in view, the invention resides in certain novel features of construction and combination and arrangement of parts, the essential features of 25 which are hereinafter fully described, are particularly pointed out in the appended claims, and are illustrated in the accompanying drawing, in which:

Figure 1 is a side elevation of a paper 30 bottle constructed according to my invention.

Figure 2 is a vertical sectional view on line 2—2 of Figure 1.

Like characters of reference refer to like 35 parts in both views.

Referring to the drawing in detail, 40 represents the cylindrical body portion of the bottle in the lower end of which a bottom 11 is crimped, a conical upper section 12 is crimped so as to form a collar 13 which 45 fits about the upper end of member 10 and is secured thereto in any suitable, convenient and effective manner. All of the parts thus far described are of paper and are impregnated with wax or paraffin to render 50 them impervious to moisture.

The cone 12 is cut away at 14 and a window 15 of celluloid or any other suitable substance is applied on the inside. This provides a means for determining the cream 55 line of the milk.

The top of the bottle is finished by a metallic ring 16 which is pressed into tight engagement with the top edge of the truncated cone 12 and which is formed with an inner annular flange 17 forming a seat for 60 the cap or top which may be of any usual and suitable form.

Particular emphasis is laid on the fact that the bottle is constructed of a shape substantially identical to the ordinary glass 65 milk bottle so that it may be handled and filled by the same machinery which is ordinarily used for this purpose, and the adoption of this form of bottle will not necessitate any change in the filling and 70 capping machinery now in use.

While I have described what I consider to be the most desirable embodiment of my invention, it is obvious that many of the 75 details may be changed without in any way departing from the spirit of my invention, and I therefore do not limit myself to the details herein shown, nor to anything less than the whole of my invention as set forth by the appended claims.

Having described my invention, what I claim as new and desire to secure by Letters Patent is:

1. In a bottle of the character described, 80 a body of cellulosic material, an upper section extending from the upper end of the body, and a reinforcing member secured about the upper end of said upper section and provided with abutment means projecting inwardly of the upper section and forming 85 a seat for reception of a closure cap pressed into the upper end of said upper section.

2. In a bottle of the character described, 90 a body of cellulosic material, an upper section extending from the upper end of the body, and a reinforcing ring secured on the upper end of the upper section and provided with an inwardly projecting annular flange forming a seat for a cap pressed into 95 the upper end of said upper section.

3. In a bottle of the character described, 100 a body, an upper section extending from the upper end of the body, and a reinforcing ring secured on the upper end of the upper section and provided with an inwardly projecting annular flange forming a seat for a cap pressed into 105 the upper end of said upper section.

4. In a bottle of the character described, a 110

paper body, a paper upper section secured on the upper end of the body, and a reinforcing and protecting ring secured upon and extending within the upper end of said upper section, said ring being provided with an inwardly projecting flange forming a seat for a cap pressed into the ring.

5. In a bottle of the character described, a paper body, and a paper upper section crimped to provide a depending flange fitting snugly about and secured on the upper end of the body.

In testimony whereof I affix my signature.
JONATHAN WAINWRIGHT, JR.
